Traxxas TRX-4M Aluminum Servo Mount (Blue), Part#: TRA9739-Blue, as shown in www.amainhobbies.com, May 18, 2023. (Year: 2023).*

(Continued)

Primary Examiner — Gino Colan*Assistant Examiner* — Gregory G McLemore(74) *Attorney, Agent, or Firm* — Daryl R. Wright; Greg Carr(57) **CLAIM**

The ornamental design for a model vehicle servo mount as shown and described.

DESCRIPTION

FIG. 1 is an upper, left, front perspective view of a model vehicle servo mount showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is an upper plan view thereof;

FIG. 7 is a lower plan view thereof;

FIG. 8 is a lower, left, front perspective view thereof;

FIG. 9 is a lower, right, rear perspective view thereof; and, FIG. 10 is an upper, right, rear perspective view of the model vehicle servo mount.

In the drawings, the broken lines illustrate portions of the model vehicle servo mount that form no part of the claimed design.
